Primary Examiner — Wan Laymon*Assistant Examiner* — Mark Booker(74) *Attorney, Agent, or Firm* — Marshall, Gerstein & Borun LLP(57) **CLAIM**

The ornamental design for a dispenser, as shown and described.

DESCRIPTIONFIG. 1 is a perspective view of a dispenser;
FIG. 2 is a front elevation view of the dispenser shown in FIG. 1;

FIG. 3 is a rear elevation view of the dispenser shown in FIG. 1;

FIG. 4 is a top plan view of the dispenser shown in FIG. 1;

FIG. 5 is a bottom plan view of the dispenser shown in FIG. 1;

FIG. 6 is left-side elevation view of the dispenser shown in FIG. 1; and,

FIG. 7 is right-side elevation view of the dispenser shown in FIG. 1.

The broken lines shown in the figures represent portions of the dispenser that form no part of the claimed design.

The broken away symbols in the drawings indicate that any portion of the article beyond what is shown forms no part of the claimed design.
